PORTABLE IRRIGATION SIPHON

Harry V. Morris, Lowell H. Morris, and James E. Morris, Dixon, Calif.

Application January 27, 1942, Serial No. 428,404

3 Claims. (Cl. 137—26)

This invention relates to the irrigation of field crops, forming a supply of water confined as a ditch between temporary levees thrown up along the field during the growing season, and particularly to a portable siphon by means of which the water may be taken from the ditch at any point and distributed between the rows of growing crops, without cutting the levees.

One of the objects of this invention is to provide a siphon of this general character constructed so that it is very light, enabling the same to be easily picked up and carried about without much effort, and yet which is so strong and rigid that it may be subjected to ordinary rough treatment without damage or the likelihood of a leak developing.

A further object is to provide a gate for the siphon, so that the flow of water therethrough may be controlled and such water allowed to issue in a quantity sufficient to thoroughly penetrate the soil, the siphon and gate being so constructed relative to each other that the gate may be readily mounted on either end of the siphon as the position of the latter relative to the ditch may necessitate, or said gate may be removed and omitted if its use is not desired at any time.

A further object of the invention is to provide a simple and inexpensive device and yet one which will be exceedingly effective for the purpose for which it is designed.

These objects we accomplish by means of such structure and relative arrangement of parts as will fully appear by a perusal of the following specification and claims.

In the drawing similar characters of reference indicate corresponding parts in the several views.

Figure 1 is a side elevation of the siphon and gate unit as disposed in place and as in operation.

Figure 2 is a fragmentary enlarged sectional elevation of the siphon and gate.

Figure 3 is a fragmentary top plan view of the unit.

Figure 4 is a cross section on the line 3—3 of Fig. 2, looking toward the gate.

Referring now more particularly to the characters of reference on the drawing, the siphon is built up of three straight sections of thin galvanized or similar pipe or tubing, the top central leg 1 being relatively short, while the legs 2 are considerably longer, are of equal length and diverge from each other at such an angle as to conveniently straddle the usual temporary

field levee 3 thrown up between the water supply and the crop growing area.

The siphon legs are cut on the bias at their adjacent ends and abut against each other, being connected and sealed against leakage by heavy continuous weld beads 4 thereabout. By means of this feature the siphon is very rigid at the joints, giving great strength and freedom from possible leakage even with considerable rough handling.

At their outer ends the legs are surrounded by identical heavy circular rings 5 about which the metal of the legs may be rolled if desired, and forming outwardly projecting beads or flanges 6. The rings not only reinforce the thin metal of the legs and prevent their collapse or distortion, but provide a smooth surface for engagement with the hand of the operator, who—when starting the siphon—closes one end of the same with the palm of the hand. A very light siphon is therefore provided, which at the same time is very strong and substantially proof against collapse or leakage by reason of the reinforcing end rings and the heavy weld beads at the joints. Also by reason of the equal length of the legs 2 either end of the siphon may be placed in the ditch.

In connection with the above described siphon I have provided a removable gate whereby the flow through the siphon may be controlled. This gate comprises a flat thin metal plate 7, longer than the diameter of the siphon, and preferably cut upwards from the bottom somewhat as at 8 and provided on top with an outwardly bent finger tab 9. Down the sides the gate is bent over in the direction opposite the tab 9, to form parallel open ended semi-circular channels or grooves 10 of substantially the same size as the outermost portions of the siphon beads 6 so that said grooves may engage either bead with a sliding friction fit.

Either bead at a time thus not only serves to reinforce the siphon but also serves as a mounting and guide means for the gate, enabling the latter to be slid up and down and retained in any position on the siphon, or to be removed entirely if an unobstructed flow is desired. The channels 10 on the gate, besides serving to support the same from the siphon, stiffen the gate vertically and allow the same to be made of thinner metal than would otherwise be the case. The cutting away of the gate at the bottom enables a relatively wide open position to be maintained while still retaining the channels 10 engaged with the circular bead 6.

From the foregoing description it will be readily seen that we have produced such a device as substantially fulfills the objects of the invention as set forth herein.

While this specification sets forth in detail the present and preferred construction of the device, still in practice such deviations from such detail may be resorted to as do not form a departure from the spirit of the invention, as defined by the appended claims.

Having thus described our invention, what we claim as new and useful and desire to secure by Letters Patent is:

1. A portable irrigation siphon comprising a central leg and end legs of equal length and angularity diverging therefrom, opposed outwardly projecting identical flange elements on both legs at their outer end, and a gate to removably and slidably engage the elements of either leg at a time.

2. A portable irrigation siphon comprising a central leg and end legs diverging therefrom, outwardly projecting continuous reinforcing beads about the end legs at their outer end, the beads of both legs being of identical size, a single gate and side channels on the gate to slidably and removably engage either bead at a time.

3. A portable irrigation siphon comprising a central leg and end legs diverging therefrom, an outwardly projecting continuous reinforcing bead secured on one end leg at its outer end, a gate, and parallel facing channels along opposed edges of the gate slidably embracing said bead at opposed points.
